UNITED STATES PATENT OFFICE.

CHARLES HENRY FRANK, OF AMSTERDAM, NEW YORK.

ELECTRIC FIRE-ALARM AND CALL-BELL SYSTEM.

SPECIFICATION forming part of Letters Patent No. 281,680, dated July 24, 1883.

Application filed May 7, 1883. (No model.)

To all whom it may concern:

Be it known that I, CHARLES HENRY FRANK, a citizen of the United States, residing at Amsterdam village, in the county of Montgomery 5 and State of New York, have invented certain new and useful Improvements in Electric Fire-Alarm and Call-Bell Systems, of which the following is a specification, reference being had therein to the accompanying drawings.

- 10 The object of my invention is to provide a system of electric call or alarm bells placed in the several rooms of a hotel or other building connected with a battery, and so constructed and connected together that in case of fire 15 those occupying the various rooms may be alarmed or called by sounding the alarm or call bells in each room by a person in the office manipulating a switch, or, in case it is desired to call an occupant of any given room 20 at a certain time, the same may be accomplished by completing the circuit through a contact bearing a number to correspond with the number of the room, thereby sounding an alarm or call in the desired room.
- 25 Referring to the drawings, Figure 1 is a general view of my invention, showing my improvements located in the various rooms of a hotel or building and upon different stories or floors, as indicated by the broken lines and 30 the several references marked thereon. Fig. 2 is a semi-sectional view of the switch-board, as shown in Fig. 1, in the room marked "Office." Fig. 3 is a modification of my invention, showing a different form of switch; and 35 Fig. 4 is a detached view of one of the contacts in Fig. 3.

The arrows indicate the directions of the currents of electricity.

I construct a switch-board, *b*, of circular 40 form, containing any given number of metal contacts *m*, (see Figs 1 and 2,) substantially of the form as shown at *m* in Fig. 2, provided with a small hole, *a*, to receive the conducting-wires *7'*, *8'*, &c. These stumps I secure in 45 a circular form upon a disk, usually of wood, as shown by the dotted lines in Fig. 1. The upper portions, *a'*, of these contacts *m* just nicely pass through the dial *b*.

In the center of the disk *b*, I secure a binding-post, *c*, provided with a hole in its lower or back end to receive the conducting-wire *K*. This binding-post *c* has a shoulder at its upper

end, so as to receive the metal lever *d*, which lever *d* is secured to the post upon the shoulder just referred to by the nut *e*. This metal lever 55 *d* revolves freely upon this post *c*, and may be placed in contact with the several points *a'*, that extend up through the dial *b*, thereby completing the circuit, as will hereinafter more fully appear. I provide this metal lever *d* 60 with a thumb-knob, *f*, for the operator to manipulate the lever with. I have shown three battery-cells, *g g' g''*, in the drawings; however, under ordinary circumstances, a single cell would be sufficient. This battery I locate in 65 the basement or in any other convenient locality. These cells are connected together with the connecting-conductors *y y'*.

Within each room of the hotel or building, as indicated by the dotted lines, (see Figs. 1 70 and 3,) I place in any convenient place an electro-magnetic bell, *n*, of the usual and ordinary construction. I do not confine myself to any particular form of bell.

From the battery I run a conductor-wire, 75 *A*, to post *h* of the electro-magnetic bell *n* in room No. 1, and from this post *h*, I extend a conductor, *B*, to post *i* on the call apparatus in room No. 2. From this post *i*, I extend a conductor to post *j* on bell apparatus in room No. 80 3. From this post *j*, I extend a conductor, *D*, to post *k* on the electro-magnetic bell in room No. 4; and I continue extending in the same manner conductors *E*, *F*, *G*, *H*, *I*, and *J* to their respective posts upon the several electro-magnetic-bells in the several rooms, numbered 85 5, 6, 7, 8, 9, and 10, respectively, as fully shown in detail in Fig. 1.

From the post *h'* on the electro-magnetic bell in room No. 1 I extend to the contact-post *m* 90 on disk *b* the return conductor-wire No. 1', and from post *i'* on the electro-magnetic bell in room No. 2 I extend the conductor-wire No. 2' to the contact-post *m* in disk *b*, all substantially as shown; and from the posts *j'*, *k'*, *l'*, *m'*, *n'*, *o'*, *p'*, and *q'* upon their respective electro-magnetic bells in the several rooms numbered, respectively, 3, 4, 5, 6, 7, 8, 9, and 10, I connect and extend to the contacts *m* the conducting-wires *3'*, *4'*, *5'*, *6'*, *7'*, *8'*, *9'*, and *10'*. 100

From binding-post *c* (see Figs. 1 and 2) I extend the conductor *K* to the battery *g''*.

The operation of my invention is as follows: The battery is of course supposed to be charged

and the currents of electricity to flow, when the circuit is complete, in the directions indicated by the several arrows. If it is desired to call any particular room—say, as an illustration, room No. 7—the operator turns the lever *d* directly over contact *m* 7, as indicated by the broken lines, and presses it down firmly. Binding-post *O'* on electric magnetic bell in room No. 7 is connected by conductor-wire No. 7' 10 with contact *m* 7 on disk *b*. The circuit is now completed through conductor-wires A, B, C, D, E, F, G, and H to the post *O* on call-instrument in room No. 7, then through the magnets of the instrument, thereby sounding the alarm 15 and calling the occupant, and passing over return-wire No. 7' to and through contact *m* 7, over lever *d*, post *c*, wire *K*, to battery. As long as the operator presses the lever *d* the alarm will continue to be sounded. When the 20 lever *d* is removed from the contact *m* 7, the circuit is broken, the current of electricity ceases to flow and the gongs to be sounded. By a repetition of this operation with any of the contacts *m*, from No. 1 to 10, inclusive, 25 the same results will be produced. This is done, as heretofore described in the case of room No. 7, by completing the circuit through the contact *m* and the respective wires leading to each room, and the lever *d*, post *c*, and wire *K*. In case of fire, and it is necessary to 30 call the occupants of each room immediately, the attendant in the office revolves the lever *d*, and as it passes each contact *m* he presses down the lever and completes the circuit, 35 thereby sounding the gongs upon each electric magnetic instrument in each room as long as the lever *d* remains in contact with the respective contacts *m*. This operation would sound the alarms in each room at intervals. 40 It will be readily seen that by the use of my improvements the guests of a hotel containing many occupants in a large number of rooms may be called or alarmed, in case of danger from fire, almost instantly throughout the whole 45 house, thereby preventing loss of life.

In large hotels each floor may be provided with my "system" connected with the office separately, or they may all be connected together, as the emergencies of the case may require. 50 I have indicated in the drawings ten rooms connected with the main office. I do not con-

fine myself to any given number of rooms. There may be ten or there may be five hundred. The operation will be the same in each 55 case.

Figs. 3 and 4 are modifications of my improvements. The connections are made substantially the same as those described, and shown in Fig. 1. The only existing differences 60 consist in the arrangements of the switch-board. In this arrangement, when it is desired to sound the bell in any particular room, the plug *b'*, attached to the flexible conductor *d'*, is inserted into the hole *b''* in the binding-post corresponding to the room. When the bells in all the rooms are to be sounded, the plug is brought in contact with the binding-posts *m'* in succession. Figs. 3 and 4 show the 65 modifications that may be made in a switch-board. However, it is evident these modifications do not change the nature of my invention. 70

In the drawings I have shown one well-known form of bell. The trembly or vibrator bell 75 may be used. In fact, any well-known elastic bell which operates upon a closed circuit or makes and breaks in a circuit can be used.

Having fully described my invention, what I claim as new, and desire to secure by Letters 80 Patent, is—

1. The combination, with a series of bells located in various places, and connections from the bells to one side of a battery and to a central office, of a switch-board, *b*, having 85 contacts *m*, forming the terminals of the various connections to the bells, and the arm *d* in electrical connection with the other side of the battery, substantially as described.

2. The combination, with a series of bells 90 located in various rooms of a hotel, and having connections with the battery and a switch-board, of a switch having connection with the battery, and a switch-board, constructed substantially as described, whereby any one of 95 the bells may be rung independently, or all may be rung in succession, as and for the purpose described.

In testimony whereof I affix my signature in presence of two witnesses.

CHARLES HENRY FRANK.
